UNITED STATES PATENT OFFICE.

JOHN FESTA, OF BROOKLYN, NEW YORK.

DESIGN FOR A HEATING STOVE.

Application filed December 13, 1921. Serial No. 522,163. Term of patent 14 years.

To all whom it may concern:

Be it known that I, JOHN FESTA, residing at Brooklyn, Kings County, New York State, and a citizen of the United States, have invented a new, original, and ornamental Design for Heating Stoves, of which the following is a specification, reference being had to the accompanying drawings, forming a part thereof, and in which—

Fig. 1 is a perspective view of a heating stove from the front and showing my new design.

Fig. 2 is a similar perspective view of the rear of a heating stove and showing the new design.

What I claim as new is:

The ornamental design for a heating stove, as shown.

In testimony whereof I hereunto affix my signature.

JOHN FESTA.
